UNITED STATES PATENT OFFICE.

JOHN BAIRD, OF NEW YORK, N. Y.

FEED-WATER HEATER FOR STEAM-BOILERS.

SPECIFICATION forming part of Letters Patent No. 460,347, dated September 29, 1891.

Application filed March 12, 1891. Serial No. 384,736. (No model.)

To all whom it may concern:

Be it known that I, JOHN BAIRD, mechanical engineer, a citizen of the United States, residing at No. 324 Lexington avenue, in the city, county, and State of New York, have invented certain new and useful Improvements in Feed-Water Heaters for Steam-Boilers, of which the following is a specification.

My invention more especially relates to steam-boilers of the class having horizontal or slightly-inclined flues. Its object is to secure a compact and efficient boiler adapted to make ample steam of high pressure in a comparatively small space, which end I attain, principally, by causing the feed-water to traverse externally and longitudinally around the boiler-shell and through the back connection or uptake and smoke-box, where it is thoroughly heated by the escaping products of combustion. The subject-matter claimed is hereinafter specified.

The accompanying drawings show my improvements as adapted to a locomotive-boiler of the type exemplified in United States Letters Patent No. 434,973, granted to me August 26, 1890, illustrating, however, so much only of the apparatus as is necessary to show the subject-matter claimed.

Unless otherwise indicated, the parts are of ordinary construction and operation.

Figure 1 is a plan; Fig. 2, a vertical longitudinal central section on the line 2 2; Fig. 3, a front elevation; Fig. 4, a back elevation; Fig. 5, a vertical transverse section on lines 5 5 and 5^a 5^a of Fig. 3, and Fig. 6 a detail view on the line 6 6 of Fig. 2.

That end of the boiler at which the furnace is situated I call the "front" end, and the opposite the "back" or "rear." That side on the left of a person facing the boiler I call the "left," and the opposite side the "right."

Soft unfeathered darts indicate the directions in which the sections are shown. Solid feathered arrows show the course of the products of combustion, and dotted ones that of the feed-water.

A fire-box A is shown as connected by a back head I with a front tube-sheet of lower shell B, through the fire-tubes b of which the products of combustion pass into the back connection or uptake A'. The front head D is composed of two parallel plates, constitut-

ing a water-space, with which various pipes are connected, as hereinafter described, and is provided with the usual fire-doors d. The 55 sides and top of the fire-box consist of a series of transverse arched water-tubes e, placed close together side by side between the front and back heads, being united at each end to longitudinal side tubes E, connecting the 60 front head and lower shell.

A series of longitudinal water-tubes F, connected at their upper ends with the front head, extend backward and downward near the bottom of the fire-box in front of the fire-tubes of the main shell, with which they are connected by suitable pipes. The fire-box is wider than the main boiler-shell, and a portion of the space thus gained is occupied by water-tubes connecting the front and back 70 heads, these tubes being preferably connected with the inner sheet of the front head and passing through packed water-tight sleeves in the back head, with which they are connected by small tubes h.

An upper shell K is shown as extending over the fire-box and lower shell. It is connected with the front head by pipes d' for the passage of mingled steam and water, with the transverse arched tubes e by small pipes 80 e', and with the lower shell by tubes k. It is also provided with return-flues k' k² and the steam-pipe L, extending through its front head. The water-level is normally below the central tubes k², so that the lower flues heat 85 the water, while the upper ones dry or superheat the steam. A casing A⁵ incloses and covers the uptake and shells, leaving a space A³ on each side of the upper shell constituting a smoke-box, which connects at the front 90 end of the boiler with the usual smoke-stack or chimney. (Not shown.) Consequently one portion of the hot gases passes through the smoke-box, while another portion passes through the return-flues, thereby heating 95 both sides of the boiler-shell K, and thus tending further to dry and superheat the steam therein.

Feed-water flows into a box M on each side of the smoke-box above the fire-box and lower shell through a pipe m, provided with a check-valve m'. Horizontal pipes M' extend through the smoke-box and connect the boxes M with similar ones M² at the back of the casing A⁵.

behind the back connection, in which boxes the water rises to a series of corresponding return-pipes M^3 , through which it passes forward to a channel M^4 , extending over the smoke-box and connected by pipes M^5 with an upper channel N , extending across the upper part of the back connection or uptake. From thence it descends through a row of small pipes n to a portion of the bottom of the uptake, whence 5 it rises through similar inclosing pipes n' to a lower channel N' , just below the upper one, whence it passes downward through a pipe N^2 , provided with a check-valve n^2 , to a water-inlet pipe N^3 , crossing the back connection or 10 uptake and connected with the main shell. The channels, the pendent feed-pipe, the inlet-pipe, and the rear end of all the longitudinal water-tubes occupy the back connection or uptake, where they are exposed to the 15 heat passing therethrough, which circulates freely around and among them, thus heating the feed-water highly before it enters the boiler.

I have found in practice that the normal 20 temperature in the uptake is about 600° Fahrenheit, of which about 200° is absorbed by the feed-water pipes, and the feed-water is heated to about 100° , the remaining 100° being apparently utilized in generating steam 25 in the boiler, owing to the detention, absorption, and reflection of the heat at this point by my improved apparatus. The boiler is of course to be supplied with the most approved appurtenances, including safety-valves and 30 steam, water, and air passages for filling and working the boiler.

The operation of the apparatus will readily be understood from the foregoing description.

I do not broadly claim herein the combination 35 of pendent feed-water-heating tubes and longitudinal feed-water tubes, such subject-matter being claimed in a prior application heretofore filed by me, Serial No. 383,854, filed March 5, 1891, patented July 28, 1891, as 40 No. 456,712.

What I claim as new and as of my own invention is—

1. The combination, substantially as hereinbefore set forth, of the fire-box, the lower shell in rear thereof, the upper shell overlying both the fire-box and lower shell, the fire-tubes of the upper and lower shells, the uptake connecting them, the smoke-box inclosing the upper shell, the chimney at the front end thereof, water-boxes at both ends of the smoke-box, pipes connecting them, through which the water flows from front to back and

forward again through the side pipes and backward through the central pipes, the upper channel in the uptake with which these 60 central pipes connect, concentric tubes pendent therefrom, a lower channel to which the water flows through these pipes from the upper channel, and the feed-water-inlet pipe passing through the uptake to the boiler. 65

2. The combination, substantially as hereinbefore set forth, of the fire-box, the lower shell in rear thereof, the narrower upper shell overlying both the fire-box and lower shell, the fire-tubes of the upper and lower shells, 70 the uptake connecting them, the smoke-box connecting the uptake and chimney and inclosing the upper shell, water-boxes in the uptake and chimney at each end of the smoke-box, the lower and upper side pipes $M' M^3$, 75 the front channel M^4 , the back upper channel, the upper central pipes M^5 , connecting these front and back channels, the lower back channel, the concentric pipes connecting the back channels and pendent therefrom in the back 80 connection, and the inlet-pipe connecting the back channels and boiler.

3. The combination, substantially as hereinbefore set forth, of the upper shell, its fire-tubes, the back connection, the front hood or 85 chimney, the smoke-box inclosing the shell, the vertical water-boxes in the front hood and back connection, the upper and lower series of side pipes $M' M^3$ connecting them, the front channel M^4 , the back upper channel N , the 90 pipes M^5 , connecting these front and back channels, the lower back channel, their concentric pendent connecting-pipes in the back connection, and the inlet-pipe passing through the back connection and connecting the lower 95 back channel with the boiler.

4. The heating apparatus hereinbefore described, consisting of the combination of water-boxes at both sides and both ends of the boiler, longitudinal pipes connecting them 100 extending through the smoke-box, through which pipes the water flows from front to back, upward and forward again through the side pipes, and backward through the central pipes, concentric pipes pendent from water-boxes crossing the uptake, and the feed-water-inlet pipe passing therethrough to the boiler. 105

In testimony whereof I have hereunto subscribed my name.

JOHN BAIRD.
